UNITED STATES PATENT OFFICE.

REINHOLD H. WAPPLER, OF NEW YORK, N. Y., ASSIGNOR, BY MESNE ASSIGNMENTS, TO WAPPLER ELECTRIC MANUFACTURING COMPANY, OF NEW YORK, N. Y., A CORPORATION OF NEW YORK.

INTERRUPTER.

1,003,222.

Specification of Letters Patent. Patented Sept. 12, 1911.

Application filed October 6, 1909. Serial No. 521,259.

To all whom it may concern:

Be it known that I, REINHOLD H. WAPPLER, a citizen of the United States, residing in the borough of Manhattan, city, county, and State of New York, have invented an Improvement in Interrupters, of which the following is a specification.

My present invention relates to an interrupter for electric circuits for use in X-ray and similar work and is an improvement upon the apparatus shown and described in Letters Patent No. 929,353, granted July 27, 1909, to the Wappler Electric Controller Company, as my assignee, for an interrupter apparatus.

The apparatus shown and described in the Letters Patent aforesaid, as well as that comprising my present invention relate particularly to mechanical interrupters for electric circuits as distinguished from electrolytic interrupters, the apparatus being designed to be employed with an alternating current such as ordinarily supplied for light and other service.

In the apparatus described in the Letters Patent aforesaid, a rectifier was employed for the purpose of making effective only the positive impulses of the electric circuit in passing through the coil to set up a flux in the magnetic circuit, so that this magnetic flux due to the effect of the rectifier, varied substantially from zero to a positive maximum.

Now in the apparatus comprising my present invention, I have dispensed with the use of a rectifier, *per se*, and employ together with the means for setting up a variable flux in the magnetic circuit, means whereby the variable flux set up in the magnetic circuit is alternately augmented and substantially neutralized electrically so that the magnetic flux in this apparatus also varies from a positive maximum to zero to operate an armature or other device for closing the magnetic circuit to operate contacts at which the make and break of the electric circuit occurs in that circuit employed for X-ray or other work.

In carrying out my present invention, I preferably employ separable make and break contacts, a magnetic circuit including means whereby the same may be made or broken, means for setting up a variable magnetic flux in the said magnetic circuit, means whereby the said magnetic flux is

alternately augmented and substantially neutralized and means operated by the opening and closing of the magnetic circuit in actuating the said separable contacts, as will be hereinafter more particularly described.

In the drawing, Figure 1 is a plan of an interrupter constructed in accordance with my present invention. Fig. 2 is a cross section on line 2, 2, Fig. 1. Fig. 3 is a side elevation and partial section showing the separable contacts and associated parts in elevation and the base in section; the figure being on a larger scale than that shown in Figs. 1 and 2; and Fig. 4 is a diagrammatic view of the circuits included in the interrupter comprising my present invention.

Referring to the drawings, the interrupter apparatus comprising my present invention is mounted upon a suitable base 10 which may be made of hard rubber or any other similar suitable material. This base 10 is provided in suitable positions with binding posts indicated at 11, 12, 13, and 14; and 15 and 16 respectively represent the end members of the frame in which are mounted an alternating current coil 17 and a direct current coil 18. The alternating current coil 17 is wound with comparatively heavy wire, whereas the direct current coil 18 is wound with relatively fine wire.

The end members 15 16 of the coil frame are connected to and supported upon the base-bars 19, 20; the opposite ends of both of which are recessed to be received in binding posts 11 to 14 inclusive; the ends of the base-bar 19 being received and clamped in the binding posts 11 and 12, and the ends of the base-bar 20 being similarly received and clamped in the binding posts 13 and 14.

21 designates a yoke preferably of laminated iron, the respective ends of which pass through and form the cores of the alternating current coil 17 and direct current coil 18 which latter is provided with binding post terminals 22, 23, from which suitable wires may be led to any convenient source of direct current of electricity.

24 represents an armature bar which at one end is suitably connected to a post 25 by means of screws 26 or otherwise, and this post 25 is journaled at its lower end in the foot 27 which is secured to the base 10. Secured to the armature bar 24 is an armature 28 which like the bar yoke 21 is prefer-

ably made of laminated iron and is placed in such a position on the armature bar 24 as to span the extremities of the limbs of the yoke 21 and come into contact with the 5 extremities thereof, and the face of the armature 28 may be provided with a strip of felt or other similar material indicated at 29. On the side of the armature bar opposite that to which the armature 28 is secured, I prefer to employ a strap indicated 10 at 30. Swiveled in this strap 30 is a button 31 and extending between the button 31 and an adjusting screw 32 is a spring 33; the adjusting screw 32 passing through the 15 parts of the split post 34; the function of the spring 33 manifestly being to normally maintain the armature bar and its armature 28 away from and out of contact with any extremities of the limbs of the bar yoke 21, 20 and the adjusting screw 32 may be secured in any desired position in the post 34 by means of the clamp screw 35 or otherwise.

36 represents a split post suitably secured in the base 10 and passing through this 25 split post 36 is a positioning screw 37, the end of which is adapted to come in contact with the face of the armature bar 24 to determine the extent of movement of the armature bar and its armature, and this positioning screw 37 may be clamped in place 30 in the post 36 by means of the screw 88 or otherwise, and manifestly in a normal condition the armature bar 24 is maintained against the end of the screw 37 by the action 35 of the spring 33.

On the base 10 is secured a suitable upright 38 provided at its opposite ends with split posts 39 40. In the post 39 there is placed an adjusting screw 41 and in the post 40 there is suitably mounted a sleeve 42. On the sleeve 42 between the posts 39 and 40 there is a collar 43 and surrounding the sleeve 42 and extending between the collar 43 and the adjacent faces of the post 40 is 45 a spring 44 the function of which is to maintain one end of the sleeve 42 in contact with the end of the adjusting screw 41. This sleeve 42 is also provided longitudinally with a recess 45 and extending through one 50 member of the split post 40 there is a pin or screw 46, the inner end of which extends into the recess 45 so that the sleeve 42 is prevented from rotating and moving revolu- 55 bly to any extent when adjusted longitudinally. Passing centrally into and secured within the sleeve 42 is a rod 47 and secured to the outer end of this rod 47 is a normally stationary but adjustable contact 48 at which the circuit for the X-ray or 60 other apparatus is made or broken. The contact 48 is provided with a collar 49 to which is connected a terminal 50 and the terminal 50 is connected to a binding post 51 of the base 10 by means of any suitable 65 electrical conductor as indicated at 52.

On the base 10 and preferably in alignment with the upright 38 is another upright 53. This upright 53 is also provided with posts indicated at 54, 55, and passing through and journaled in the posts 54, 55, and in 75 alignment with the rod 47 is a rod 56. Between the posts 54 and 55 the rod 56 is provided with a collar 57 and extending between the collar 57 and the adjacent face of the post 54 and surrounding the rod 56 there 75 is a spring 58. On the rod 56 exteriorly of the post 55 is a contact 59 similar in all respects to the contact 48 and between which as aforesaid an electric current is made and broken. The contact 59 is also provided 80 with a collar 60 to which is secured a terminal 61 and extending between the terminal 61 and the binding post 62 secured in the base 10 there is an electrical connection 63 similar to the connection 52, the 85 collar 57 abutting against the adjacent face of the post 55 forms a stop for the rod 56 and the terminal 59, and exteriorly of the post 54 there is secured to the rod 56 a cross-piece 64, which may be secured in position 90 thereon by being passed over a reduced screw threaded end of the rod 56 which is provided with a nut 65 or otherwise.

Secured in and extending from the post 54 I may employ a pin 66 which also passes 95 slidably through an aperture provided therefor in the cross-piece 64 in order to prevent the revoluble movement of the rod 56 and its terminal contact 59 in the reciprocating movement thereof.

The hereinbefore described parts are so placed that the outer or free end of the armature bar 24 extends under the rod 56 and is adapted to contact with the cross-piece 64 so that in the vibrating movement 105 of the armature bar 24 and its armature during the operation of the apparatus a reciprocating movement will be imparted to the rod 56 and its contact 59; the right to left movement being effected by the attraction of the armature and the left to right movement being effected by the spring 58.

The base 10 is provided with terminal contacts 67, 68 to which the terminals of a condenser 69 may be electrically connected 115 and the base 10 is also provided with binding posts 70, 71, between which a suitable resistance 72 for the alternating current coil may be electrically connected. On the base 10 there are also binding posts designated by the numerals 1, 2 and 3.

The terminals of any suitable alternating current conductor indicated at 73 are connected to the binding posts 2 and 3 in the use of the apparatus. The binding post 3 is 125 connected to the binding post 51 by a wire 74 and the binding post 51 is connected to the binding post 67 by a wire 75; the binding post 68 being connected to the binding post 62 by a wire 76 and the binding post 130

62 is connected to a binding post 1 by a wire 77.

Between the binding posts 1 and 2 there are connected in the circuit an induction coil 5 whose primary winding is indicated at 78 and a secondary winding is indicated at 79, a suitable resistance 80 and a switch 81; the wire 82 leading from one terminal of the switch to the binding post 2.

10 A wire 83 connects the binding post 3 with the binding post 11 and the base-bar 19 of the magnet frame to which also is electrically connected one end of the alternating current coil 17, the other end of 15 which coil is electrically connected to the base-bar 20 which as will be understood is connected electrically with the binding post 14 from which a wire 84 is connected to the binding post 70.

20 Between the posts 70 and 71 there is as aforesaid a resistance 72 and a wire 85 is electrically connected between the binding post 71 and the terminal 86 to the switch 81; the terminal 87 of the switch being the 25 one which is as aforesaid connected by the wire 82 to the binding post 2.

The direct current coil 18 in the use of the apparatus has its binding posts 22, 23, electrically connected across the terminals 30 of any suitable source of direct current electricity hereinafter called circuit *a*. Manifestly the circuits supplied by the alternator 73 are in parallel; the one passing by way of the terminal 3 through the wire 83 35 to the post 11, through the alternating current coil 17, the post 14 by way of the wire 84, post 70, through the resistance 72, post 71, through the wire 85, the switch 81, wire 82, binding post 2 back to the opposite 40 terminal and alternator 73, hereinafter called circuit *b*, and the other circuit in parallel is by way of the wire 74, through the post 51, through the connection 52 to the contact 48 and the contact 59; the connection 45 63 to the post 62, the wire 77, to the binding post 1, through the primary 78 of the induction coil, through the resistance 80, through the switch 81 by the wire 82 from both circuits to the binding post 2 in 50 the opposite terminal of the alternator 73 hereinafter called circuit *c*.

Now it will be manifest that in the circuit *b* through the alternating current coil 17 the current varies from a positive to a 55 negative maximum and consequently the effect of this coil on the yoke and core of the magnet is to set up a magnetic flux therein which will also vary from a positive to a negative maximum, and thereby 60 the armature of the yoke will be attracted twice during each cycle of the current, that is, once for each reversal of the current, but the direct current coil in circuit *a* is so designed that the current therein will set up 65 a magnetic flux in the yoke core of the

magnet which will tend to augment the flux set up by the positive impulse of the alternating current in the alternating current coil in circuit *b* and to substantially neutralize the magnetic flux set up by the 70 negative impulse of the alternating current by the alternating current coil in this circuit, whereby only the positive impulse of the alternating current is employed in actuating the apparatus to separate the contact points in circuit *c*, and by this arrangement I am enabled to obtain a slow make and a sudden break of the circuit at these contact points 48, 59.

I claim as my invention:

1. An interrupter comprising separable make and break contacts, a U-shaped magnetic core, a direct current coil on one limb of the said core, an alternating current coil on the other limb of the said core and 85 means operative through the influence of the magnetic flux set up in the said core by the passage of electric currents through said coils for actuating the said contacts to make and break an electric circuit. 90

2. A circuit interrupter comprising separable make and break contacts, a magnetic circuit including means whereby the same may be opened and closed, an alternating current coil and means for supplying an 95 alternating current for setting up an alternating magnetic flux in the said magnetic circuit, means whereby the magnetic flux set up in the magnetic circuit is alternately augmented and substantially neutralized, 100 and means actuated by the said means whereby the magnetic circuit may be opened and closed for operating the said contacts to make and break an electric circuit thereat. 105

3. A circuit interrupter comprising a base, separable make and break contacts thereon, a magnet core, an alternating current coil for setting up a variable magnetic flux in the said magnet core, means whereby said magnetic flux set up in the said magnet core is alternately augmented and substantially neutralized, a device adapted to be attracted to the said magnet core to close the magnetic circuit therethrough, 110 means for moving the said device in the opposite direction for normally maintaining the same in such position that the said magnetic circuit is open, means operated by the movement of the said device for actuating 115 the said variable contacts to make and break an electric circuit thereat. 120

4. A circuit interrupter comprising a base, separable make and break contacts thereon, a magnet core, means for setting 125 up a variable magnetic flux in the said magnet core, a direct current coil wound on said magnet core to alternately augment and substantially neutralize the variable magnetic flux set up in the said magnet 130

- core, a device adapted to be attracted to the said magnet core to close the magnetic circuit therethrough, means for moving the said device in the opposite direction for 5 normally maintaining the same in such position that the said magnetic circuit is open, means operated by the movement of the said device for actuating the said variable contacts to make and break an electric circuit 10 thereat.
5. A circuit interrupter comprising a base, separable make and break contacts thereon, a yoke magnet core, an alternating current coil on one limb of the said magnet core for 15 setting up a variable magnetic flux therein, a direct current coil on the other limb of the said magnet core for alternately augmenting and substantially neutralizing the variable magnetic flux set up in the said magnet core 20 by the alternating current coil, a device adapted to be attached to the said magnet core to close the magnetic circuit therethrough, means for moving the said device in the opposite direction for normally maintaining the same in such position that the 25 said magnetic circuit is open, means operated by the movement of the said device for actuating the said variable contacts to make and break an electric circuit thereat.
- 30 6. A circuit interrupter comprising a base, separable make and break contacts thereon, a yoke magnet core, an alternating current coil on one limb of the said magnet core for setting up a variable magnetic flux therein, 35 a direct current coil on the other limb of the said magnet core for alternately augmenting and substantially neutralizing the variable magnetic flux set up in the said magnet core by the alternating current coil, an armature 40 pivotally mounted and adapted to swing against the extremities of the limbs of the said magnet core to close the magnetic circuit therethrough, means for moving the said armature in the opposite direction and 45 means operated by the movement of the said armature for actuating the said separable contacts to make and break an electric circuit thereat.
7. A circuit interrupter comprising a base, 50 separable make and break contacts thereon, a yoke magnet core, an alternating current coil on one limb of the said magnet core for setting up a variable magnetic flux therein, a direct current coil on the other limb of the 55 said magnet core for alternately augmenting and substantially neutralizing the variable magnetic flux set up in the said magnet core by the alternating current coil, an armature pivotally mounted and adapted to swing 60 against the extremities of the limbs of the said magnet core to close the magnetic circuit therethrough, means for moving the said armature in the opposite direction, means for adjusting and determining the extent of movement of the said armature and

means operated by the movement of the said armature for actuating the said separable contacts to make and break an electric circuit thereat.

8. A circuit interrupter comprising a base, 70 separable make and break contacts thereon, a yoke magnet core, an alternating current coil on one limb of the said magnet core for setting up a variable magnetic flux therein, a direct current coil on the other limb of the 75 said magnet core for alternately augmenting and substantially neutralizing the variable magnetic flux set up in the said magnet core by the alternating current coil, an armature pivotally mounted and adapted to swing 80 against the extremities of the limbs of the said magnet core to close the magnetic circuit therethrough, means whereby the said armature is moved in the opposite direction, a spring for moving the armature in the opposite direction, means for varying the tension of the said spring and means operated by the movement of the said armature for actuating the said separable contacts to make and break an electric circuit thereat. 85

9. A circuit interrupter comprising a base, a post mounted on said base, a sleeve slidably secured in said post, means for adjusting the said sleeve to a predetermined position in the said post, means for preventing the turning of said sleeve within the said post during the adjustment thereof, a contact connected to the said sleeve, a movable contact mounted in alinement with the aforesaid contact, a magnetic circuit including means whereby 90 the same may be made and broken, means for setting up a variable magnetic flux in the said magnetic circuit, means whereby the said variable magnetic flux is alternately augmented and substantially neutralized 95 and means operated by the opening and closing of the said magnetic circuit for reciprocating the said movable contact to make and break an electric circuit between the same and the first aforesaid contact. 100

10. A circuit interrupter comprising a base, a post mounted thereon, a sleeve slidably mounted in said post and provided longitudinally in the surface with a recess, a pin passing through said post into the said recess to prevent the turning of the said sleeve in the longitudinal movement thereof, a collar on the said sleeve, a spring surrounding said sleeve and extending around said collar and the adjacent face of said post, a contact secured to the said sleeve, means for adjusting the said sleeve and the contact against the action of said spring to a predetermined position, a movable contact mounted in alinement with the aforesaid contact, a magnetic circuit including means whereby the same may be made and broken, means for setting up a variable magnetic flux in the said magnetic circuit, means whereby the said variable magnetic flux is 115 120 125 130 135

alternately augmented and substantially neutralized and means operated by the opening and closing of the said magnetic circuit for reciprocating the said movable contact to make and break an electric circuit between the same and the first aforesaid

Signed by me this 30th day of September 1909.
